[57] ABSTRACT

A rotary bar guide assembly for a door locking mechanism having a front guide plate disposed against a backing plate with both plates being secured together and to a door panel adjacent a horizontal edge of same, the front and backing plates having complementary portions offset forwardly from the plane of the door panel. A rotary locking bar being adapted to extend vertically between the two plates. The backing plate laterally confines the front plate and has a slot engageable by a lip formed on a rotary locking bar.

ROTARY BAR GUIDE ASSEMBLY

BACKGROUND OF THE INVENTION

1. Field of the Invention

My present invention pertains to a guide assembly for the rotary locking bar of a door locking mechanism of the type used on trucks and cargo containers of the types presently being used in rail, sea, air and road transit.

2. Description of the Prior Art

The prior art rotary bar guide assemblies known to be in current use comprise a planar backing plate and a front guide plate adapted to confine a rotary locking bar therebetween. No provision has been made in such assemblies for close-to-the-door-edge mounting or for positively restricting lateral movement between the two plates. Further, the known guide assemblies have not made adequate provision whereby a portion of any axial racking forces exerted on the rotary bar in either direction are taken up by the guide assembly.

SUMMARY OF THE INVENTION

My present invention is concerned with a guide assembly for the rotary locking bar of a door locking mechanism which overcomes the foregoing disadvantages of presently known guide assemblies. Specifically, the guide assembly of my present invention is characterized by backing and front plates which have complementary forwardly offset portions which permit mounting the assembly close to the top or bottom edge of a door panel with, for instance, the offset portions overlying a wider than normal door sealing gasket. The offset portions further permit providing slot means on the backing plate in which an annular lip formed on the bar end of a rotary locking bar is engageable whereby axial racking forces on the locking bar are partially taken up by the backing plate bolted to the door panel. The backing plate of my invention further has means for positively preventing any lateral shifting movement between the front and back plates.

BRIEF DESCRIPTION OF THE DRAWINGS

FIG. 1 is a partial front elevational view of a rotary bar door locking mechanism showing a preferred embodiment of the rotary bar guide assembly of my present invention;

FIG. 2 is a horizontal sectional view taken generally along line 2—2 of FIG. 1;

FIG. 3 is a horizontal sectional view taken generally along line 3—3 of FIG. 1;

FIG. 4 is a vertical sectional view taken generally along line 4—4 of FIG. 1 with the front guide plate removed;

FIG. 5 is a perspective view of the front guide plate of FIG. 1;

FIG. 6 is a perspective view of the backing plate shown in FIGS. 2 and 4;

FIG. 7 is a perspective view of a split plastic bearing used in the embodiment of FIG. 1; and

FIG. 8 is a perspective view of a modified backing plate.

DESCRIPTION OF THE PREFERRED EMBODIMENTS

Referring now to FIGS. 1 through 4, there is illustrated the lower portion of a rotary bar door locking mechanism 20 having a rotary bar guide assembly 22

embodiment my present invention. The door locking mechanism 20 includes a rotary locking bar 24 having a forged bar end 26 secured to the bottom end thereof in a known manner. The bar end 26 is characterized by a pair of axially spaced annular lips 28 and 30 and by a radially projecting locking finger 32 at its lower end. The lower end of the locking bar 24 and the upper portion of the bar end 26 are rotatably retained on a door panel 34 by the guide assembly 22.

10 The locking finger 32 is adapted to be engaged in a keeper member 36 mounted on a portion of a door frame member 38, as best illustrated in FIGS. 1 and 3. The keeper member 36 is characterized by a U-shaped body portion 39 and outwardly directed flanges 40 which are secured to the door frame member 38 by suitable fasteners 42. The locking finger 32 is engageable with the keeper member 36 through suitable slots 44 formed in side portions 46 of the U-shaped body portion 39. It is understood that the upper end of the 20 rotary locking bar 24 is provided with a bar end having a locking finger engageable in a keeper member as well as a guide assembly, which latter is identical to the guide assembly 22.

The new and novel rotary locking bar guide assembly 22 of my present invention includes a backing plate 48, a front guide plate 50, both of which may be formed of 25 10 gauge steel stampings, and, in the embodiment of FIG. 1, a split plastic bearing 52a, 52b. For reasons that will be discussed hereinafter, the locking bar guide assembly 22 of my present invention is particularly well adapted for close-to-the-door-edge installations as, for instance, where for various reasons it is not practical to use bolts or screws immediately adjacent the door edge or where a wider-than-normal sealing gasket is secured 30 to the door edge. The guide assembly 22 disclosed herein may even have a portion thereof extending past the door edge.

As best illustrated in FIG. 6, the novel backing plate 48 is characterized by a first planar portion 54 which 40 is adapted to be disposed flush against the door panel and by a generally planar portion 56 which is offset forwardly of the first planar portion 54 and spaced away from the plane of the door panel 34. The offset portion 56 is disposed at the end of the backing plate 48 adjacent to the edge of the door panel 34 and is connected to the first planar portion 54 by an integral inclined portion 58. A plurality of bores 60 are provided along the sides of the first planar portion 54 of the backing plate 48 for securing same to the door panel 34.

The front guide plate 50, which is generally complementary to the backing plate 48, is characterized, as best illustrated in FIG. 5, by a generally semi-cylindrical vertically disposed central portion 62 and by a pair of side flanges 64 adapted to be seated flush against the backing plate 48 along the side edges thereof. A portion of the guide plate side flanges 64 are forwardly offset, as at 66, complementary to the offset portion 56 of the backing plate 48 including integral complementary inclined flange portions 68. The side flanges 64 of the front guide plate 50 are provided with a series of bores 70 which are aligned with the bores 60 provided in the backing plate 48 so that the backing and front guide plates 48 and 50 may be secured together and to the door panel 34 by suitable fasteners, such as bolts 72.

The forwardly offset side flange portions 66 of the front guide plate 50 are each provided with at least one

through bore 74 whereby to facilitate spot-welding the front plate 50 to the forwardly offset portion 56 of the backing plate 48 to further strengthen the connection therebetween. To prevent lateral movement of the front guide plate 50 relative to the backing plate 48, embracing flanges are provided on one of said plates to abut against the side edges of the other plate and, as illustrated, the offset portion 56 of the backing plate 48 is provided at its side edges with forwardly projecting flanges 76 which abut against the side edges of the forwardly offset side flanges 66 of the front guide plate 50 whereby to laterally confine same therebetween.

In the embodiment of the guide assembly 22 shown in FIG. 1, the split plastic bearing 52a, 52b (FIG. 7) is provided for the rotary bar 24, the bearing 52a, 52b being disposed between the semi-cylindrical portion 62 of the front guide plate 50 and the backing plate 48, as shown in FIG. 2. The bearing portions 52a, 52b are provided on their rear surfaces with mating rearwardly projecting semi-cylindrical bosses 78a, 78b. The backing plate 48 is provided with a cylindrical bore 80 which is adapted to receive both of the semi-cylindrical bearing bosses 78a, 78b whereby to properly align the split plastic bearing 52a, 52b relative to the backing plate 48.

The backing plate 48 is provided on the first planar portion 54 with a rotary bar guide member 82, which is spaced above the split plastic bearing 52a, 52b, and on the forwardly offset portion 56 with a rotary bar guide groove 84.

As best illustrated in FIGS. 4 and 6, the forwardly offset and inclined portions 56 and 58, respectively, of the backing plate 48 are provided with a horizontally disposed slot or notch 86 which is adapted to receive a portion of the annular lip 28 formed on the bar end 26. With the lip 28 engaged in the slot or notch 86, a portion of any axial racking forces exerted on the ends of the rotary bar 24 are transmitted to the door panel 34 through the backing plate 48 and the mounting bolts 72 whereby to partially relieve the racking forces on the bar 24, the locking fingers 32, and the keeper members 36.

In some instances it may be preferred that the split plastic bearing 52a, 52b not be used. In this case, a modified backing plate 148 (FIG. 8) may be utilized. The backing plate 148 is quite similar to the backing plate 48 and is characterized by a first planar portion 154 having mounting bores 160 and a bar guide member 182, by an inclined portion 158, and by a forwardly offset portion 156 having forwardly projecting side flanges 176, a lip engaging notch or slot 186, and a bar guide groove 184. The backing plate 148 differs from the backing plate 48 in that the bar guide member 182 has a greater vertical length than the guide member 82. To further compensate for the non-use of a plastic bearing, the bar guide groove 184 may be shallower than the guide groove 84 and the bar guide member 182 may be spaced a greater distance from the planar portion 154 than the guide member 82.

While I have shown and described what I believe to be two preferred embodiments of my present invention, it will be understood by those skilled in the art that various rearrangements and modifications may be made

therein without departing from the spirit and scope of my invention.

I claim:

1. In a rotary bar door locking mechanism, an improved rotary bar guide assembly comprising,
  - a backing plate having a first planar portion adapted to be seated against a door panel and a second generally planar portion offset forwardly of said first planar portion and spaced from the plane of said door panel adjacent a horizontal edge of said door panel,
  - a mating front guide plate having a generally semi-cylindrical vertically disposed central portion whereby to accommodate a portion of a rotary bar between said central portion and said backing plate and having a pair of side flanges adapted to be seated flush against said backing plate along the side edges thereof, a portion of said guide plate side flanges being forwardly offset complementary to said offset portion of said backing plate, and
  - slot means provided in said backing plate and adapted to receive a portion of an annular lip formed on the rotary bar.
2. A guide assembly as recited in claim 1 wherein means are provided on one of said plates for laterally confining the other plate, said confining means comprises a pair of forwardly projecting flanges formed on the sides of said forwardly offset portion of said backing plate and adapted for abutting engagement with the side edges of said offset portions of said side flanges of said front guide plate.
3. A guide assembly as recited in claim 1 wherein a split plastic rotary bar bearing is disposed between said backing plate and said generally semi-cylindrical central portion of said front guide plate, each portion of said split plastic bearing is provided on its rear surface with a rearwardly projecting semi-cylindrical boss and wherein said backing plate is provided with a cylindrical bore adapted to receive both of said semi-cylindrical bearing bosses whereby said split plastic bearing is properly aligned relative to said backing plate.
4. In a rotary bar door locking mechanism, an improved rotary bar guide assembly comprising,
  - a backing plate adapted to be seated against a door panel adjacent a horizontal edge thereof,
  - a mating front guide plate having a generally semi-cylindrical vertically disposed central portion whereby to accommodate a portion of a rotary bar between said central portion and said backing plate and having a pair of side flanges adapted to be seated flush against said backing plate,
  - a plurality of aligned bores provided in said guide plate side flanges and said backing plate so that same may be bolted together and to said door panel,
  - rotary bar guide means on said backing plate,
  - slot means provided in said backing plate and adapted to receive a portion of an annular lip formed on a rotary bar, and
  - means on one of said plates for laterally confining the other plate.
